UNITED STATES PATENT OFFICE.

FRANK D. WILT, OF ALLENTOWN, PENNSYLVANIA.

ELEVATOR SAFETY DEVICE.

1,373,285.

Specification of Letters Patent. Patented Mar. 29, 1921.

Application filed September 18, 1918. Serial No. 254,649.

To all whom it may concern:

Be it known that I, FRANK D. WILT, a citizen of the United States of America, residing at Allentown, in the county of Lehigh and State of Pennsylvania, have invented new and useful Improvements in Elevator Safety Devices, of which the following is a specification.

The purpose of the invention is to provide a safety device for use with those kinds of elevators using a control cable for starting and stopping, the device having means for locking the control cable at the time the landing doors are open. The locking means is controlled by the landing doors and requires that the doors be closed to shift it to the unlocking position so that the control cable may be rendered operative for starting the car.

Other and further purposes of the invention appear in the following description wherein the same is set forth in detail. While illustrated and described as a safety device for use in swinging doors, the invention is not to be restricted to such use. It is adaptable to sliding doors as well as swinging doors and these specific elements shown to accomplish the object of the invention may be varied in the details of construction without departing from the spirit of the invention. Therefore, the right is reserved to make any such variations in detail as may be comprehended in spirit by the appended claims.

The same numerals of reference designate the same parts throughout the several figures of the drawings, wherein:

Figure 1 is a perspective view showing the practical application of the invention to an elevator shaft whose landings are provided with double swinging doors.

Fig. 2 is a front elevational view of the control cable locking means, the cover therefor being shown in open position.

Fig. 3 is a section on the line 3—3 of Fig. 1.

Fig. 4 is a bottom plan view of the door locking bolt keeper and its attendant mechanism.

Fig. 5 is an end view of the structure shown in Fig. 4.

Fig. 6 is a section on the line 6—6 of Fig. 2.

Fig. 7 is a section on the line 7—7 of Fig. 2.

Fig. 8 is a section on the line 8—8 of Fig. 1.

Fig. 9 is a perspective view of a modified form for operating the locking device.

Fig. 10 is a perspective view of the application of the invention to a sliding door.

Fig. 11 is a detail sectional view of the locking elements employed in the structure shown in Fig. 10.

Referring to the drawings and particularly to Fig. 1, there is shown an elevator shaft in the vicinity of a landing which is closed by the swinging doors 1. The car movable in the shaft is of the character controlled by a cable and, therefore, a section 70 of the cable 2 is shown. In the vicinity of the landing, there is attached to the cable 2 a bar 3, the clamping members 4 being provided for the purpose of attaching this bar 3 to the cable. The clamping members 4 consist of two elements secured together by screws 5, the attachment of these screws serving to secure the clamping members to the bar 3 as well as to the cable 2, as clearly shown in Fig. 8.

For the purpose of guiding the bar 3 and providing a means for mounting other mechanism coöperating with the bar, there is a base plate 6 secured to the wall of the elevator shaft by appropriate screws 7. 85 This plate 6 carries guiding rails 8 positioned one adjacent each edge of the bar 3, so that the latter may be restricted to vertical movement only in the shaft, as the cable 2 is raised or lowered for the purpose of 90 starting or stopping the car which it controls.

The clamping members 4 which secure the bar 3 to the cable are of a character to hold the bar spaced away from the cable, so that 95 it parallels the cable throughout the length of the bar.

Mounted upon the plate 6 adjacent one of the rails 8 there is a member simulating a bell-crank lever in shape. This member is 100 provided with a short arm 9 and a weighted portion 10 constituting the other arm, the member being pivotally mounted on the stud 11. The shorter arm 9 of this member pivotally connects with the locking bar 12, the 105 arm 9 sustaining the weight of the locking

bar at the end adjacent the bar 3. The extreme end of this locking bar is formed with rack teeth engageable with the rack teeth 14 formed on one edge of the bar 3. In order that the teeth of the locking bar may be insured engagement with the teeth 14 of the bar 3, there are provided the plates 15 secured one on either side of the locking bar adjacent its end, but projecting beyond the end of the latter and straddling the bar 3, so that there may be no lateral movement of the locking bar that might make for poor engagement between its teeth and the teeth 14. A hollow cover member 13 hingedly attached to the plate 6 serves, when brought in contact with the plate to inclose the weighted element, the toothed portion of the bar 3 and the toothed end of the locking bar. This hollow member 13 is appropriately recessed as shown at 13^a and 13^b, so that both the bar 3 and the locking bar 12 and the cable 2 may pass into and out from under the hollow cover. It is obvious from the construction of the bell-crank element that the weight 10 serves normally to keep the locking bar in engagement with the bar 3 and so long as such engagement exists, all vertical movement of the bar 3 is precluded and therefore the cable 2 may not be moved. Thus if this engagement is caused to take place at the time when the car is at rest, the car may not be started until the disengagement of these parts.

The construction provides for this disengagement only at the time when the doors 1 are closed and both must be closed and locked before such disengagement can be effected. To that end, at the top of the door frame adjacent to that side of the shaft at which the control cable 2 is carried, there is mounted a bearing member 16. Likewise at the top of the door frame but approximately in the middle of the same there is mounted a second bearing 17, the latter being cast integral with the keeper plate 18 from which it is spaced, as shown in Fig. 4. In the bearings 16 and 17 there is journaled a shaft 19 and this shaft at one end—that projecting just out of the bearing 16—carries an arm 20. Mounted on the front wall of the shaft adjacent the door opening and on that side thereof adjacent the control cable 2, there is carried a bracket member 21 secured in place thereon by bolts 22 which pass through elongated holes 23 formed in the bracket member. It is obvious, that by loosening the bolts 22 a certain amount of vertical adjustment of the bracket may be obtained for the proper positioning of the counter shaft 24 which is carried by the bracket. This counter shaft 24 is operatively connected with the arm 20 and with the locking bar 12. For this purpose the shaft 24 carries the arm 25 with which one end of a link 26 pivotally con-

nects, the remaining end of the link being pivotally connected to the bar 20 at its end. The shaft 24 further carries an arm 27 with which the locking bar 12 at its end pivotally connects. 70

It is obvious that the rocking of the shaft 19, by means of the connection between it and the locking bar 12, will serve to disengage the teeth of the locking bar from the teeth 14 or to permit the weight 10 to effect this engagement. Such a rocking movement is imparted to the shaft 19 by means of the door locking bars 28. Each of the doors 1 carries one of these locking bars 28 and each door, therefore, carries a base plate 29 near its upper edge and this base plate carries a slide bearing 30 formed with a threaded stud 31 which effects engagement with the base plate. This threaded engagement between the stud and the base plate is loose enough to permit pivotal movement of the slide bearing 30 when the door locking bar is raised or lowered. 80

On each door and positioned at a point convenient to reach, there is carried an operating medium for the door locking bars 28. This operating medium comprises a base plate 32 appropriately attached to the door and a bent lever 33 pivotally carried on the stud 34 secured to the base plate. This bent lever 33 on one side of the pivot stud 34 is formed with a handle 35, the portion 36 of a handle being made relatively heavy as compared with the remaining. The bent end of the lever pivotally connects with the door locking bars 28. It is apparent that when the bent lever 33 lies in a horizontal position, the door locking bar 28 is raised to its highest position, at which time it engages behind the keeper plate 18 to secure the door in locked position. It is also apparent that the shifting of the lever 33 to a vertical position moves the door locking bar 28 to a position where its free end may pass beneath the keeper plate 18. A stud 37 mounted on the base plate 32 limits the lever 33 to the horizontal position to maintain the extended position of the locking bar 28. 100 105 110

That the door locking bars 28 may operate to rock the shaft 19 and thereby release the locking bolt 12 from the bar 3, there is provided a collar 38 secured on the shaft 19 on that end projecting beyond the bearing 17. This collar 38 is formed with a radially projecting stud 39 on which there is carried a swivel member consisting of two plates 40 united by a web 41, the web being pivotally mounted on the stud 39. The two plates 40 are substantially S shaped in cross-section and on their lower faces may be engaged by the free ends of the locking bars 28 when the latter are raised to locking positions behind the keeper plate 18. If but one locking bar 28 is raised, such as would be the case were but one door locked, the 115 120 125 130 135

swivel member would rock on its pivotal stud 39 and there would be no movement of the shaft 19 as a result. When the other door is locked, however, that end of the 5 swivel plate previously raised may not lower, but the other end of the swivel plate is forced raised by the locking bar 28 of the door being closed. Therefore the pivot stud 39 must move to permit this end of 10 the swivel plate to raise to make room for the locking bar. But the movement of the pivot stud 39 imparts an angular movement to the shaft 19 with the result that the connections between it and the locking bar 12 15 are operated so as to disengage the teeth of the locking bar from the teeth of the bar 3, therefore releasing the cable 2 so that the car which it controls may be put in motion. So long as the doors are locked, the 20 locking bar 12 is disengaged from the bar 3, but immediately upon unlocking one or both of the doors, the weight 10 is permitted to operate to reengage the locking bar 12 and bar 3, thus locking the control cable 2 until 25 the doors 1 be again locked.

The bearings 17 and 16 and the shaft 19 are appropriately inclosed within a housing 42 whose front wall 43 is inclined downwardly and outwardly from the elevator 30 shaft. This housing 42 is made preferably of sheet metal and the front wall 43 is formed with a flange portion 44 secured to the front wall of the shaft just above the door opening.

35 Mounted upon the doors 1 there are the angular shaped brackets 45 and these brackets carry the plates 46 diagonally disposed with reference to the inner faces of the doors, the plates being in alinement with 40 the outer wall 43 of the housing 42 and their faces lying flush with the face of the front wall 43 of the housing 42. The plates 46 inclose the locking bars 28 for a certain portion of the length of the latter and, therefore, 45 openings 47 are formed in the plates so that the locking bars may be extended therethrough to reach the bent lever 33.

The plates 46 and the front wall 43 of the housing provide means for deflecting objects projecting from the elevator platform away from the door openings as it is passing the latter and further than this they 50 serve to inclose and protect those parts of the device which would be liable to damage 55 were they not so inclosed.

In Fig. 9 there is shown a modification of the invention. This modification comprises substantially all the parts shown in Figs. 1 to 8 except the door locking bars 28 and 60 their attendant parts. In this modification, the bearing 17 is formed with a base plate 50 for attachment to the top part of the door opening, no keeper plate being provided in conjunction with the bearing in 65 this form, the modification being for the

character of both doors 51 which are held in locked position when closed by locking means 52 securing the free edges of the two doors together.

The swivel plate and its attendant parts 70 are mounted on the shaft 19 in the same way as in the form shown in Fig. 1, but this swivel plate has a different position relative to the doors from that which it has in Fig. 1. That the swivel plate may be operated to effect rocking of the shaft 19, each of the doors 51 carries an L shaped member 53 designed for engagement with the plates 40 to operate the swivel plate and release the cable 2 in the manner heretofore described.

In Fig. 10 the invention is shown applied to a sliding door 60. This sliding door carries a locking member 61 engageable in a keeper plate 62, the connection of the locking member with its keeper plate being in the nature of a hooking engagement, as clearly shown by the peculiar shapes of the parts concerned. Mounted on one side of the door opening near the top thereof there 90 is a bell-crank lever 63 and a rod 64 pivotally connects with one arm of this bell-crank lever while the end remote from the said lever is slidingly held behind the keeper 62, this end being provided with a foot 65 95 engageable with the end of the locking member 61 when the latter engages the keeper. The locking bar 12 is replaced by the locking bar 66 which engages with the bar 3. This locking bar 66 is offset, as shown, so 100 that the end remote from the bar 3 may pivotally connect with the remaining arm of the bell-crank lever 63.

When the locking member 61 is disengaged from the keeper 62, the door 60 is unlocked and therefore the weight 10 operates to keep the locking bar 66 in engagement with the teeth 14, thus precluding any movement of the cable 2. When the door 10 is closed, however, and the locking member 61 105 engages the keeper 62, it engages also the foot 65, thus forcing the rod 64 downwardly to rock the bell-crank lever 63 and move the locking bar 66 to a position where its teeth no longer engage the teeth of the bar 3.

110 The invention having been described what is claimed as new and useful is:

1. In a device of the class described, the combination with an elevator control cable, of a bar secured thereto and provided with 115 teeth on one edge, a locking bar also having teeth engageable with the first said teeth, a weighted member pivotally mounted on one wall of the elevator shaft and supporting near its toothed portion the locking bar, 120 whereby the locking bar is held normally in engagement with the first said bar, and means remote from the locking bar to move it to unlocked position, for the useful purpose specified.

2. In a device of the class described, the combination with the control cable of an elevator, of a bar carried by the cable, the bar being provided with teeth on one edge, a locking bar having teeth engageable with the first said teeth, gravity operative means for supporting the locking bar near one end and causing it normally to effect engagement with the first said bar, a rock shaft for mounting in the elevator shaft above the door openings therein, connections between said shaft and the locking bar, a pair of door locking members for mounting one on each of two doors, and means carried by the rock shaft whereby the same may be rocked by the locking members but only when both assume locked positions.

3. In a device of the class described, the combination with the control cable of an elevator, of a bar carried by the cable, the bar being provided with teeth on one edge, a locking bar having teeth engageable with the first said teeth, gravity operative means for supporting the locking bar near one end and causing it normally to effect engagement with the first said bar, a rock shaft for mounting in the elevator shaft above the door openings therein, connections between said shaft and the locking bar, a pair of door locking members for mounting one on each of two doors, and a swivel plate carried by the rock shaft and engageable by

either or both of the door locking members, so that the movement of the door locking members to closed position is required to 35 impart movement to the rock shaft and thus release the said locking bar.

4. In a device of the kind described, the combination with an elevator control cable, of releasable locking means for said cable, 40 operating members connected with said means, a swivel plate carried by one of said members, the two being operatively connected and a latching element for attachment one on each of a pair of swinging 45 doors, both of said latching elements being engageable with said swivel plate in the manner and for the purpose specified.

5. In a device of the kind described, the combination with the control cable of an 50 elevator, of locking means operatively connected with the cable and embodying a locking bar, a weighted lever pivotally mounted on the wall of the elevator shaft and operatively connected with the locking bar, a pair 55 of door locking members for mounting one on each of two doors, and means operatively connecting both door locking members with said locking bar in the manner and for the purpose specified.

In testimony whereof I affix my signature.

FRANK D. WILT.
